UNITED STATES PATENT OFFICE.

HENRY E. MOORE, OF BOSTON, MASSACHUSETTS, ASSIGNOR OF ONE-HALF OF HIS RIGHT TO GEORGE S. BURTON, OF SAME PLACE.

BUTTON FOR CUFFS, &c.

SPECIFICATION forming part of Letters Patent No. 225,853, dated March 23, 1880.

Application filed February 12, 1880.

To all whom it may concern:

Be it known that I, HENRY E. MOORE, of Boston, in the county of Suffolk and State of Massachusetts, have invented new and useful Improvements in Buttons for Cuffs and for other purposes, of which the following is a specification.

This invention relates, primarily, to that class of buttons known as "cuff-buttons;" but the button produced may be used in many other connections, such as collar-buttons, studs, &c., and I propose to use it wherever it may be deemed desirable.

The object of the invention, particularly when used as a cuff-button, is to provide a button which may be easily and readily inserted and fastened without danger of loss, whether of the whole or a part thereof, and, consequently, which can be readily removed.

The nature of the invention is described below, and in the accompanying drawings is illustrated.

Figure 1 is a plan of the under side of the button, the cover having been removed, in position to be inserted in the button-hole. Fig. 2 is a similar plan of the button in the position assumed when in use. A portion of a cuff and the button-hole therein are represented by broken lines. Fig. 3 is a cross-section of the button when in a cuff, the section being taken longitudinally through the button-holes. Fig. 4 is an elevation of the button in the position shown in Figs. 2 and 3.

Similar letters of reference indicate like parts.

a is the main portion or front of the button, provided with the flange *a'*. A post, *b*, is rigidly set into the part *a*, and is surmounted with a horizontal bar, *c*, usually integral with the post, and constituting a rigid T-shaped post, *b c*.

d is a tubular post surrounding the post *b*, and provided with wings *d' d'*, as shown in the drawings. At its base it spreads into a plate, *e*, which lies upon the inner side of the button *a*, and is provided with indentations *e'*, preferably curved in shape.

Springs *f* lie between the plate *e* and the

flange *a'*, their bent ends resting in the curved indentations *e'* in the plate *e*. A cover, *g*, usually lies upon the springs in order to give finish to the button.

x represents a portion of a cuff, and *y* the button-holes therein.

The operation of the button is as follows: Take the button in the position shown in Fig. 1, pass the part *c* of the rigid post *b c* through the button-hole of the cuff until the winged post *d d'* lies therein, then turn the main portion *a* one-fourth of a rotation, when the button will be in the position shown in Figs. 2 and 3. The portion of the cuff next the button-holes holds the winged post *d d'*, the springs *f* being pressed back out of the indentations *e'* in the plate *e*, and dropping into the next indentations when the quarter-rotation has been accomplished. The winged post *d d'* and plate *e e'* remain stationary, being held in the button-hole while the rest of the button is being rotated. At the end of the quarter-rotation the part *c* of the rigid post lies across the button-holes, and thus holds the button in position.

To release the button, give it a quarter-rotation in either direction.

One second is sufficient time in which to apply or remove the button, and the advantage over separable buttons, in which there is constant danger of the loss of a portion, is apparent.

The strength of the springs is, of course, adjusted with regard to the stiffness of the fabric to which the buttons are to be applied.

The springs may be one or more in number and of any suitable shape, and the plate *e* may be of various shapes—even a square plate would not be inoperative—as desired. About the shape shown, however, is perhaps the best.

Having thus fully described my invention, what I claim, and desire to secure by Letters Patent, is—

1. In a button for cuffs, &c., the combination, with the main portion *a* of the button and the T-shaped post *b c*, of the tubular embracing-post *d*, provided with one or more

wings, d d' , adapted to be held stationary in the button-hole while the rest of the button is rotated, substantially as set forth.

2. In combination with the T-shaped post b c and flanged button-top a a' , the winged embracing-post d d' , provided at its base with a plate of irregular shape, and one or more

springs placed between said plate and the flange a' , constructed and arranged substantially as and for the purpose described.

HENRY E. MOORE.
